UNITED STATES PATENT OFFICE.

RICHARD P. BROWN, OF PHILADELPHIA, PENNSYLVANIA, ASSIGNOR TO THE BROWN INSTRUMENT COMPANY, OF PHILADELPHIA, PENNSYLVANIA, A CORPORATION OF PENNSYLVANIA.

CONTROL INSTRUMENT.

Application filed October 29, 1924. Serial No. 746,710.

The general object of my present invention is to provide an improved control instrument of the type in which the actuation of one or more electric switches by a tilting 5 depressor or other intermittently operating power actuator is made dependent on the position of the movable element of a galvanometer or other meter. In instruments of the type referred to, the control switch or 10 switches are commonly employed for one or more of the following purposes; to wit, the operation of signals, the adjustment of resistances and marker elements of potentiometer and analogous indicator recorders, and 15 the regulation of the supply of heat to a furnace in response to temperature variations therein to which the meter is responsive. As heretofore ordinarily constructed the meter pointer in an instrument of the 20 type referred to has served as a means through which the depressor or other power actuator has transmitted to the controlled switch, the energy required for actuating the latter. In accordance with the present invention, the controlled switch is directly engaged and actuated by the depressor or other 25 power actuator in a certain position or range of positions of the movable element of the control meter, while the latter in another position or range of positions prevents the 30 movement of the power actuator into operative engagement with the last mentioned switch. As a result of this difference the present invention possesses certain important practical advantages as will appear from 35 the following description.

The invention may be employed in an instrument in which the only control switch is the switch directly engaged by the depressor or power actuator as above described, but in a preferred embodiment of the invention the instrument comprises one or more additional switches which are actuated in the usual manner heretofore followed by the power actuator through the instrument pointer in certain predetermined positions of the pointer. In such an instrument the additional switch or switches serve as, or as a 45 part of, the means through which the instrument pointer prevents the power actuator from operatively engaging the switch directly actuated by said actuator, except when 50

the movable element of the meter is in the position or range of positions in which the last mentioned switch should be actuated. 55

An instrument of the kind just described is especially well adapted for controlling the supply of heat to a furnace in response to the furnace temperature. In such use the switch directly actuated by the depressor 60 may serve to turn on or increase the supply of heat when actuated, and a depressor arresting switch may serve to interrupt or decrease the supply of heat when actuated. In consequence the position of the last mentioned 65 switch determines the maximum temperature normally obtained in the furnace, and by adjusting the position of that switch, the maximum furnace temperature may be varied as conditions make desirable, while the range of 70 positions of the instrument pointer in which the heat increasing switch is directly actuated by the depressor, will include the entire range of movement of the pointer at the low temperature side of the temperature limiting switch regardless of the adjustment of 75 the latter. In consequence the instrument may automatically control the operation of the furnace in starting from the cold condition as well as to maintain a close regulation 80 of the furnace temperature in regular operation.

The various features of novelty which characterize my invention are pointed out with particularity in the claims annexed to 85 and forming a part of this specification; but for a better understanding of the invention, however, its advantages and specific objects attained with its use, reference should be had to the accompanying drawings and descriptive matter in which I have illustrated 90 preferred embodiments of my invention.

Of the drawings:

Fig. 1 is a perspective view of a control instrument with parts broken away; 95

Fig. 2 is a somewhat diagrammatic plan view of a portion of the apparatus shown in Fig. 1;

Fig. 3 is a diagrammatic view with parts of the instrument shown in elevation; 100

Fig. 4 is a view generally similar to Fig. 2 illustrating a modified construction;

Fig. 5 is a section on the line 5—5 of Fig. 4;

Fig. 6 is another view taken similarly to Fig. 2 illustrating another modification;

Fig. 7 is an elevation of the apparatus shown in Fig. 6; and

5 Figs. 8 and 9 are plan views each showing a part which may be employed in the apparatus of Figs. 6 and 7.

In the particular embodiment of the invention shown in Figs. 1, 2 and 3 of the drawings, A represents a galvanometer or milli-volt meter mounted in a case a and comprising a movable element carrying a pointer A' swinging about the suspension axis of said element in accordance with variations in the quantity measured by the meter. This quantity in the case of a pyrometer may well be the E. M. F. of a thermo-couple, or the difference between that E. M. F. section of a thermo-couple and the potential drop in a pyrometer resistance section or other balancing circuit. a' represents the instrument scale along which the free end of the pointer A' moves.

Associated with the meter proper is a pointer depressor B shown as pivotally connected to the frame work at the meter B' and intermittently actuated in a known manner, as by means of a member B² and a motor H, to alternately lift the arc-shaped body b of the depressor above the path of movement of the free end of the pointer A', and then to permit the body portion b to descend under the action of gravity and thereby depress the end of the pointer A' and through its projection A¹⁰ actuate one or another of the control switches as hereinafter explained.

In accordance with the present invention a control switch G is mounted on the meter frame work out of the normal path of movement of the pointer A', but in position to be engaged and to have its normally separated contacts g brought together, by the depressor B in the final portion of each full down swing of the latter. The depressor B is prevented by the pointer A' from swinging down far enough to operatively engage the switch G, when the pointer A' is above an abutment or stop located beneath a portion of the path along which the pointer swings. As shown, this abutment or stop is in the form of a table C supported by an arm C' which is angularly adjustable about the axis of the movable element of the meter. A pointer C² carried by the arm C' indicates on the scale a' the setting or adjustment of the table C.

In the instrument shown in Figs. 1, 2, and 3, the table C supports a switch E comprising normally separated contacts e which are brought together by the instrument pointer A' whenever the latter is above the switch E at the instant the depressor B moves downward into engagement with the pointer and thereby forces the latter against the switch E. As shown, the table C also sup-

ports a switch F similar to and alongside the switch E, and similarly actuated to bring its normally separated contacts f together when the pointer A' is above the switch F at the instant at which the pointer is engaged and depressed by the depressor B.

As already explained, the control switches E, F, and G are capable of use in various ways and for various purposes. In the diagrammatic illustration of one use of the instrument shown by way of example in Fig. 3, the switches E, F, and G are associated in a control system comprising a pair of electro-magnets I and J in such manner that the magnet J will be energized when the switch E is closed and the magnet I will be energized when either of the switches G and F is energized. In this arrangement the closure of the switch E energizes the magnet J from a source of current K through circuit connections comprising a conductor 1, switch contacts e, conductor 3, and conductor 2; the closure of the switch F energizes the magnet I through a circuit comprising conductor 1, switch contacts f, conductor 4, and conductor 2; and the closure of the switch G energizes the magnet I through a circuit comprising conductor 1, contacts g, conductor 5, and conductor 2.

As diagrammatically illustrated in Fig. 3, the magnets I and J operate a control device L which may be, for example, a fuel valve, a heating current control switch, or a relay controller, to increase or diminish the supply of heat to a furnace having a pyrometric control of which the control instrument forms a part, accordingly as the lever connecting the armatures of the magnets I and J is turned in one direction by the energization of the magnet I and in the opposite direction by the energization of the magnet J.

In the instrument shown in Figs. 1, 2, and 3, the switch G serves in effect to extend the range of movement of the pointer A' in which its depression by the depressor B will effect the energization of the magnet I to include all positions of the pointer A' at the left or low temperature side of the switch F, without interfering with the adjustment of table C necessary to vary the temperature at which the instrument will cause the switch E to be actuated and thereby energize the magnet J. It will be apparent that the omission from the instrument shown in Figs. 1, 2, and 3 of the switch F and the portion of the table C beneath that switch would not effect the control of the magnets I and J, but would merely increase the range of positions of the pointer A' in which the depressor could operatively engage the switch G. While the switch F may be omitted as shown in Figs. 4-7 and its omission is advantageous from the standpoint of simplifying the apparatus, the retention of the switch is sometimes desirable,

as with it the pointer A' is not subjected to as great a bending movement when the magnet I is energized through the switch F as through the switch G, and in normal operation the pointer A' will be above the switch E or switch F except when the apparatus is being started into operation.

In the instrument shown in Figs. 1, 2, and 3, it will be apparent that if the instrument pointer A' were permitted to swing to the right or high temperature side of the abutment formed by the table C, a subsequent downward movement of the depressor B would cause the switch G to be closed under a condition in which that switch should remain open. This may be prevented in the apparatus shown in Figs. 1, 2, and 3, by the provision of a stop C³ carried by the table C which prevents the pointer A' from 20 swinging to the right of the table C. When the instrument pointer A' is thus prevented from swinging to the right of the stop C³, the pointer can no longer indicate the true value of the quantity measured by the meter. This ordinarily is not a practically serious defect, for the condition giving rise to a tendency to move the pointer A' against the stop C³ would seldom occur in ordinary use as the width of the switch E is ordinarily at least as great as the range of movement of the pointer beyond the normally neutral position of the pointer which of course is that adjacent the adjacent edges of the switches E and F. In Figs. 4, 5, 6, and 35 7 I have illustrated arrangements in which the stop C³ is omitted and the pointer A' is permitted to swing to the right of the switch E without a resultant improper actuation of the switch G.

40 In Figs. 4 and 5 wherein the switch F as well as the stop C³ is omitted, the table C is provided with an extension C⁵ at the high side of the contact E. In the top of the extension C⁵ is an arc shaped channel or groove C⁶ into which the arc shaped body b of the depressor BB extends when the depressor B moves downward, unless the pointer A' is above or at the high side of the contact E, in which case the pointer prevents the depressor from entering the groove C⁶. The switch E and table extension C⁵ thus operate to prevent the actuation of the switch G by the depressor body b except when the pointer A' is at the low temperature side of the switch E.

When the contemplated angular adjustment of the table C is relatively large and it is undesirable to provide space in the instrument case for a table extension C⁵ long enough to accommodate the full range of adjustment of the table C, the extension C⁵ may be supplemented or replaced by other means. For example, as shown in Figs. 6 and 7, the extension C⁵ may be replaced by 60 a part C¹⁰ in the form of an arc shaped bar

having a channel C¹¹ similar in shape and purpose to the channel C⁶ of Figs. 4 and 5. The member C¹⁰ is supported at one end by the table C, and adjacent its other end rests a projection A² from the instrument frame 70 work. Advantageously the member C¹⁰ is detachably connected to the table C as by means of dowel pins C¹² carried by the table and passing through apertures provided in the member C¹⁰. This arrangement permits of a considerable range of adjustment in the position of the table C without unduly enlarging the width of the casing necessary to accommodate the portion of the member C¹⁰ at the right of the support A² over 75 which the member C¹⁰ slides as the table C is adjusted. Further adjustment of the table C may be accommodated by replacing the member C¹⁰ by a longer piece C¹⁰⁰ as shown in Fig. 8, or by a shorter piece C¹⁰¹ 80 as shown in Fig. 9.

While in accordance with the provisions of the statutes I have illustrated and described the best forms of my invention now known to me, it will be apparent to those skilled in the art that changes in form may be made without departing from the spirit of my invention as set forth in the appended claims, and that some features of my invention may sometimes be used to advantage without a corresponding use of other features.

Having now described my invention, what I claim as new and desire to secure by Letters Patent, is:

1. In a control instrument, the combination with a meter pointer, of a control device, an intermittently operated actuator adapted on each operation to actuate said device unless prevented from operatively engaging the latter, and means cooperating with said pointer to prevent the actuator from operatively engaging said device in certain normal positions of said pointer but ineffective to prevent such engagement in other normal positions of said pointer.

2. In a control instrument, the combination with a meter pointer, of a control device, an intermittently operated actuator adapted on each operation to actuate said device unless prevented from operatively engaging the latter, and means cooperating with said pointer to prevent the actuator from operatively engaging said device in certain normal positions of said pointer but ineffective to prevent such engagement in other normal positions of said pointer, said means being adjustable to vary the pointer position in which the said actuator is prevented from operatively engaging said device.

3. In a control instrument, the combination with a meter pointer, of an intermittently operating actuator, a switch operated by said actuator through said pointer in one

position of the latter, and a second switch directly operated by said actuator in another position of said pointer.

4. In a control instrument, the combination with a meter pointer, of an intermittently operating actuator, a switch directly operated by said actuator in certain positions of said pointer, and a second switch operated by said actuator through said pointer in another position of said pointer and then preventing said actuator from operating the first mentioned switch.

5. In a control instrument comprising a swinging meter pointer, an intermittently tilted depressor, a stop co-acting with said pointer in certain positions of the latter, to limit the tilting movement of the depressor, and to control device operated by the depressor when the tilting movement of the depressor exceeds that to which it is limited by said stop in said certain positions of said pointer.

6. In a control instrument, the combination with a meter pointer, of an intermittently operating depressor, a stop adjustable along the path of movement of the needle and co-operating with said pointer to limit the operation of said actuator when said pointer is above said stop and a control device operated by said actuator when said pointer is not above said stop.

7. In a control system, a meter having a swinging pointer, a switch disposed along the path of movement of the pointer, an intermittently operating actuator adapted to engage the pointer and thereby actuate said switch through the pointer in one position of the latter, and a second switch directly actuated by said actuator when said pointer is out of the position for actuating the first mentioned switch.

8. In a control system meter having a swinging pointer, an intermittently operating pointer depressor, a stop adjustable along the path of movement of the needle co-operating with the pointer to limit the depressing movement of the depressor when the pointer is above the stop, one or more control switches carried by the stop and each adapted to be actuated by the depressor and the pointer when the latter is above it, and another switch adapted to be actuated by the depressor on each depressing movement of the latter not arrested by the pointer and the stop.

9. In a control instrument, the combination with a meter pointer, of an intermittently operated actuator, two switches se-

lectively controlled by said actuator according to the extent of movement of said actuator, and means dependent on the position of said pointer for determining the extent of movement of said actuator.

10. In a control instrument, the combination with a swinging pointer and an intermittently operated depressor, of control provisions comprising means dependent on the position of the pointer for limiting the depressing movement of the depressor in one position of the pointer and for permitting a greater depressing movement of the depressor in another position of the pointer, and including two control devices one of which is actuated by the depressor when its depressing movement is so limited and the other actuated by the depressor when the greater depressing movement of the latter is permitted.

11. In a control instrument, the combination with a meter pointer normally free to deflect in a plane, of an actuator normally at one side of said plane, means periodically giving said actuator a movement transversely of said plane into engagement with said pointer, means dependent upon the deflection of said pointer when engaged by said actuator for selectively limiting the extent of said movement of said actuator according to the deflection of the pointer, circuit controlling means operated by said actuator on the movement of the actuator occurring in one position of the pointer, and other circuit controlling means operated by said actuator on a movement of the latter greater than that required for the actuation of the first mentioned means.

12. In a control instrument, the combination with a meter pointer normally free to deflect in a plane, of an actuator normally at one side of said plane, means periodically giving said actuator a movement transversely of said plane into engagement with said pointer, means dependent upon the deflection of said pointer when engaged by said actuator for selectively limiting the extent of said movement of said actuator according to the deflection of the pointer, and a relay mechanism selectively controlled by said actuator for exerting one or another of two opposing effects accordingly as said extent of actuator movement does or does not exceed a predetermined amount.

Signed at Philadelphia, in the county of Philadelphia, and State of Pennsylvania, this 27th day of October, A. D. 1924.

RICHARD P. BROWN.
